[57] CLAIM

The ornamental design for a child's cassette recorder and player combination, as shown and described.

DESCRIPTION

FIG. 1 is a front perspective view of a child's cassette recorder and player combination embodying our new design;

FIG. 2 is an enlarged front elevational view thereof, the coiled cord which is partially shown is understood to repeat uniformly throughout the circumscribed area;

FIG. 3 is a right side elevational view of FIG. 2;

FIG. 4 is a top plan view of FIG. 2;

FIG. 5 is a bottom plan view of FIG. 2;

FIG. 6 is a left side elevational view of FIG. 2;

FIG. 7 is a rear elevational view of FIG. 2;

FIG. 8 is a front perspective view of a second embodiment of the design of FIG. 1;

FIG. 9 is an enlarged front elevational view of FIG. 8;

FIG. 10 is a right side elevational view of FIG. 8;

FIG. 11 is a top plan view of FIG. 8;

FIG. 12 is a bottom plan view of FIG. 8;

FIG. 13 is a left side elevational view of FIG. 8; and,

FIG. 14 is a rear elevational view of FIG. 8.
